UNITED STATES PATENT OFFICE.

JAMES E. BANCROFT, OF TOLEDO, OHIO, ASSIGNOR TO TOLEDO COMPUTING SCALE COMPANY, OF NEWARK, NEW JERSEY, A CORPORATION OF NEW JERSEY.

VULCANIZER.

1,141,519.

Specification of Letters Patent. Patented June 1, 1915.

Application filed July 5, 1910. Serial No. 570,318.

To all whom it may concern:

Be it known that I, JAMES E. BANCROFT, a citizen of the United States, residing at No. 665 Spring street, Toledo, in the county 5 of Lucas and State of Ohio, have invented a new and useful Vulcanizer, of which the following is a specification.

This invention relates to heat applying and limiting means and a knock down clamp 10 device.

This invention has utility when embodied in a vulcanizer which, due to the ease and certainty of manipulation coupled with feature of small packing space required there- 15 for, imparts special value to it as a device to be carried especially with pneumatic tire vehicles.

The objects of my invention are accom- 20 plished as hereinafter described and illus- trated in the drawings in which—

Figure 1 is a section through a vulcanizer constructed in accordance with my invention, showing an inner tube in position upon the thermal plate. Fig. 2 is an end elevation 25 showing a tire or casing clamped in position upon the vulcanizer for repairs upon its tread. Fig. 3 is also an end elevation showing the clamp arms adjustable to bear at an angle upon the thermal plate to vul- 30 canize patches upon the sides of tires and showing a supplementary bearing block interposed between the sides of the tires. Fig. 4 is a side elevation of my vulcanizer, showing an inner tube in place. Fig. 5 is an end 35 elevation showing my vulcanizer folded. Fig. 6 is a cross section through a modified form of my vulcanizer showing the pad in end elevation. Fig. 7 is a top plan view of the base. Fig. 8 is a transverse section 40 through the base on line $z-z$ of Fig. 7. Fig. 9 is a cross section through the base on line $y-y$ of Fig. 7. Fig. 10 is a plan view of the top of the thermal plate. Fig. 11 is a top view of the pad used in connection with 45 this vulcanizer. Fig. 12 is an isometric view of the supplementary pressure block. Fig. 13 is a detail in section of the adjustable clamp bar. Fig. 14 is an enlarged view of 50 the clamp arm centrally slotted or flat- tened to receive the clamp bars. Fig. 15 is a section on line $z-z$ of Fig. 4, showing the locking bars in position to engage the notches of the pressure bar casing. Fig. 16 55 is a transverse section of an anchor member provided with longitudinally extending tu-

bular reservoirs; Fig. 17 is a similar view to Fig. 16, but in which the reservoirs are spaced down in the combustion chamber from the heat conducting or thermal plate region; and Fig. 18 is a detail view showing 60 pawl to engage the primary or reciprocable set device for the clamp.

The base A of my vulcanizer is formed like a pan of some depth and has at each corner a leg 1 to provide an air space under 65 its bottom. In the area of said base is located a well 2, the side and end walls of which are parallel with the respective walls of the base and form conjointly with them an annular space 3 around the well. The 70 cross section of the well is preferably in the form of a semi-circular trough and its side walls are so pierced with ports 4, that the outlet of said ports are disposed above the bottom 5 of the annular chamber 3 and their 75 inlets open into the air space under the bottom of the base. The base is further provided with a fuel duct 6 which has its inlet 7 disposed at a side of the base and has its outlet 8 located in an end wall of the well, 80 facing the well area and being above the rim of the well walls to permit a burner B being thread-coupled thereto.

The vaporizing tube 9 of the burner is 85 thread-coupled to the outlet port 8 and extends from said port, lengthwise of and above the area of the well, over the opposite end of the base and near the opposite wall 2' of the well, said vaporizing tube is 90 provided with a valve seat 10 and a valve 11 which is controllable from the outside of the base. The vaporizing tube has also an integral drop section 12 located in the outside 95 of the valve seat, and from said drop section 12 is extended a perforated burner tube 13, which is located within the well area, under the rim of its wall and is parallel with the vaporizing tube 9. In the space between the vaporizing tube and the 100 perforated burner is located a diaphragm 14, which is suitably supported in position upon the top of the walls of the well and is provided with perforations 15 which are located along the margin of its sides adjacent to the sides of the well.

The top C or anchor member link of the clamp has depending walls 16 adapted in width and length to be telescoped within the area impounded by the walls of the base and when said top is supported by its walls 110

upon the bottom 5 of the base, there is formed a combustion chamber D in the volume of which the annular space 3 is included and the top of which forms the thermal or heat conducting or heat defining plate 17.

The side walls of the top are each provided with vent ports 18, and to deflect the escaping gases away from a tire or tube 10 upon the thermal plate, said top is provided at each side with an up flared marginal overhang 19.

Along each side of the thermal plate 17 is formed a top recess or moisture supply 16 reservoir 20 of suitable depth. From the under side of the thermal plate of the top C depends also a vaporizer E for water, comprising a drop tube or water reservoir 21 having a restricted opening 22 directly into 20 one of the side recesses, while the opposite recess 20 is connected to the drop tube by means of a lateral duct 23, the outlet 24 of which equals the restricted area of the drop tube. Said drop tube is of a length to extend through the combustion chamber D, through the bottom 5 of base A, and is adapted to serve as means to couple the base A and the top C by being extended through a bored boss 25, integral with said base, 30 which boss is provided with a winged set screw 26 adapted to impinge upon the wall of the drop tube or stem when the latter is in various adjusted positions within the bore through the boss. The adjustment permits not only a change in the size of the combustion chamber and bringing of the heat conducting plate toward or away from the burner, but in opening up between the base A and anchor member C of the vulcanizer support, may allow of draft regulation for the burner.

27 designates bail shaped longitudinally extending link clamp elements or arms, one to each side of the top C. The respective 45 ends of the arms are pivotally secured to the respective ends of the flared side overhangs 19, and one of said bail arms is provided with opposite slab in-cuts 28 to reduce its area for some distance about midway of the 50 length of the lateral portion 29 of said arm.

30 designates cross bars or clamp link elements, each having end bosses which are bored to receive the lateral portion of the respective bail arms. The bosses 31 of said 55 bails are cut to form a gap 32 of an area adapted to receive the slabbed portion 28 and when in position upon the slabbed portion, the bar may be moved to adjacent opposite and intact portions of the arm and thereby be movably coupled to the slabbed arm. The opposite bosses 33 are incut to 60 form a gap 34 of a width adapted to receive the intact bail arm 27 with slight pressure. 65 Each cross bar is also provided with a central boss 35 each of which is vertically

bored to movably receive the pressure bar F. Each central boss 35 is also provided with a lateral incut 36 which extends into the bore of the boss. In each in-cut is located a locking clamp 37 each of which is 70 movably attached to the respective boss. Said ratchet bars or locking clamps are drawalbe in the in-direction by means of winged nuts 38, one of which is thread-coupled to each ratchet bar or locking clamp in position to 75 abut the respective side of their bosses opposite to the incuts 36.

Each of the pressure bars F comprises a casing 39, which is provided with ratchet serrations or teeth 40 into which the respective ratchet bar 37 may be screw locked after vertical adjustment of the casing.

Within the bore of the casing is movably housed a stem 41 having a head 42 movable within the counterbore or tube 43. 80 The stem stud or element 41 is not necessarily rotated by the screw 44 and is of a length to have its bottom portion extended beyond the casing when the head of the stud rests upon the bottom of the counterbore. 90 The counterbore of each casing is also threaded near its top to receive the pressure screw 44 which may be brought to bear upon the head of the stud 41 after the casing is adjusted and locked in the desired position. 95 The container 45 for the caloric or fuel is coupled to the inlet port 7 by means of a pipe 46 and is provided with a closure top 47.

49 designates a pad or porous vapor diffusing permeable heat confining body, the body of which is of an absorbent fabric, such as asbestos, and is of a size to cover the area of the top. Said pad has a central bearing plate 50 adapted to contact with the thermal plate and is provided with a cavity 51 more or less approximating a plane for the material of the patch previously cemented in place at the place to be repaired and vulcanized, and said heat conducting plate is shown as provided with an annular flange, in this instance shown as separate and forming a flexible metallic rim 52, which is yieldable to the body of a tire or tube pressed thereon. The capacity of the fuel container is such, that its contents are exhausted when the repair patch is thoroughly vulcanized to the body of the tire or tube and the capacity of water chamber is also so fixed or predetermined as to exhaust with, or more or less after the exhaust of the fuel supply.

By thus proportioning the capacity of the respective reservoirs, a tire or tube may be repaired in patches without liability of the surrounding material being damaged by 125 overheating.

The saturated steam vapors which diffuse through the body of the pad, and escape along the margin of the top ensheath the clamped portion of the tire or tube and per-

mit of only such portions of a tube or tire to contact with the thermal plate as is required for good patching.

53 designates a pressure plate which is imposed over a tire or a tube to receive and distribute over the tire or tube, pressure applied by the stems, said plate being used for patches on tubes or on the tread of tires.

To vulcanize a patch to a side 54 of a tire, I have provided a supplementary block 55 which is interposed between the sides of a tire G and with plate 53 imposed thereon or to the top pressure may be applied from the clamps without unduly distorting the body of the tread of a tire, said pressure being transmitted through the body of the side 56 of the tire G and the interposable block 55 to the side 54 of the tire, which is thereby pressed upon the thermal plate.

20 By pivoting the arms to the body of the top, pressure may be applied to a tire or tube at an angle to the top of the thermal plate to compensate for the side-wise inclined position of either the plate 53 or both the block 55 and the plate 53, which is imparted to either, plate 53, or block 55 and plate 53 by the crosswise taper of the body of a tire or tube, which is clamped upon the thermal plate of the vulcanizer.

30 The pivotal connection of the top bar to each of the arms, and of the arms to the anchor element constitutes a series of three links of the clamp, which series is completed by the anchor clamp element as the forth link.

By providing a ratchet adjustment to the pressure bars they may be rapidly adjusted to varying thicknesses of tires and tubes, and thereby not only permitting the application of pressure by means of the screws with a minimum of turns, but also facilitating the removal of a tube or tire from the vulcanizer after a repair patch is vulcanized.

45 For free initial setting, the pawl 37 is released, or the sleeve F rotated to prevent cylindrical face or untoothed portion to the pawl, and the sleeve then forced to setting position, from which point the locked device may be acted upon by the rotary power applying clamp element 44. These clamp devices F are spaced from each other and independently adjustable, primarily by the ratchet mechanism and finally by the thumb screws.

55 As the clamp arms are detachably connected by means of the cross bars, the placing in position of tire or tube upon the thermal plate of my vulcanizer and the removal therefrom is rapidly accomplished.

60 In the use of my vulcanizer, the water chamber is filled with water, the fuel reservoir is also filled. The pad is placed over the area of the heat conducting element or thermal plate, and the material which has received a patch, is placed adjacent the heat

zone defining means as bounded by the heat confining device. The freeable ends of the cross bars are then connected to the respective arm and after adjusting the pressure bars by means of the ratchets, pressure 70 is applied upon the heat conducting element opposing means or plate 53 or the plate and the block 55 by means of the screws, thereby flexing the rim around the area of a patch. Well 2 subserves also as a starting 75 pan H. A fixed quantity of fuel is permitted to escape into the well, which quantity is ignited, through a suitable opening, in a side or an end wall of the top, to initially heat the vaporizing tube upon which its contents, replenishable from the fuel reservoir, are permitted to escape as vapors through perforated burner tube until the contents of the reservoir are exhausted. Said escaping vapors are initially ignited by the exhaust 80 starting flame in the well or may be ignited through the same opening. The burning vapors in the combustion chamber heat the thermal plate and by conduction effect the vulcanization of the material of 85 the patch to the damaged portion of the tire. The water in its reservoir is gradually evaporated to provide a wet steam shroud or envelop for the body of the tire or tube around the portion to be vulcanized and protects a tire or tube against being burned in 90 said sound portions. This moisture had the effect of preventing injury to the rubber of the tire being vulcanized about the point of repair by reducing the temperature, in case 95 for any reason the heat of the burner should become too great, but has been found to favorably affect the rubber at the point of vulcanization in some way, the precise action of the moisture not being at present known 100 to me.

After the patch material is vulcanized to the body of the tire or tube, which is accomplished when the fuel supply is exhausted, and the vulcanizer has cooled, the tire or 110 tube is removed from the vulcanizer by releasing of the screw pressure and detaching the bosses of the cross bars from the clamp arm 27' upon which the arm may be swung apart and the tire or tube removed. But if 115 more patches are needed upon the body of the same tire or tube, the operation as above described is repeated, the water and fuel reservoir are filled and material for another patch is placed in the cavity of the central 120 pad plate without the tire or tube being removed from the vulcanizer by shifting in place the other portion to be patched; and for the purpose of another or more vulcanizations of the same tire or tube, the tire or 125 tube, after the screw pressure is relieved, the ratchet lock of the clamp bars are released to permit the tire being raised vertically a suitable distance for filling the water reservoir and supplying fuel, after which, the 130

tire or tube is turned to locate another patched or cemented damaged portion over the heat zone defining means, and is then again clamped in position, and the operation 5 of vulcanizing is repeated.

The ratchet pressure bars F may be bodily detached from their bores in the cross bars and with said cross arms uncoupled from the clamp arm 27, both arms may be folded 10 upon the top of the thermal plate to reduce the vulcanizer into a compact package with the fuel reservoir and its outlet pipe turned to locate the reservoir along the respective side of the base.

15 In the modification shown in Fig. 6, the water chamber and the fuel chamber are omitted. A sufficient quantity of fuel is placed in the well, being held therein by an absorbent material, packed in the area 20 of the well, and the wet steam for the protecting envelop for a tube or tire is provided by water absorbed by dipping of the body of the pad or saturating it in place upon the vulcanizer thermal plate.

25 In the modification shown in Fig. 16, the top 56 is provided with integral water chambers 57, having openings 58 adapted to feed a pad imposed upon the thermal plate 59 and in the modification shown in Fig. 17 the 30 thermal plate is provided with drop tube evaporators 60 and in Fig. 18 is shown a modified form of a ratchet lock for the clamp bars, comprising a spring pressed pawl 61.

35 What I claim is—

1. A vulcanizer comprising a body having an internal combustion chamber, a burner, and a reservoir for fuel, said chamber having its top adapted to form a thermal plate, and provided with a cavity for the material for a patch, a bail-like arm so pivotally coupled to each side of the body as to locate the respective lateral connecting bar of each bail above the respective side 45 of the body and parallel therewith, a pair of cross bars pivoted to one of the bails and movable lengthwise thereon adapted to detachably engage the lateral bar of the opposite bail, and means depending from each 50 cross arm adapted to be brought to bear upon the thermal plate.

2. A vulcanizer comprising a body having an internal combustion chamber, there being a cavity for the material for a patch 55 over the combustion chamber, a burner and a fuel reservoir pipe connected to said burner and provided with a controlling valve, clamping means comprising a bail pivoted to each side of the body and one or 60 more cross-bars movable upon the lateral bar of the respective bail, each cross-bar having an end pivotally coupled to the lateral arm of one of the bails and the opposite end detachably coupled to the lateral

arm of the opposite bail, pressure means 65 depending from each cross-bar toward the top of the combustion chamber comprising an upward lockable ratchet sleeve, a top headed stem movable within the bore of the sleeve, and a pressure screw bearable upon 70 the head of the stem.

3. A vulcanizer comprising an inclosed combustion chamber provided with means for generating heat, a supplementary top 75 imposable over the combustion chamber, said top having a metallic container for the material for a patch and having inherent interstices for the diffusion of vapors, a water container depending from the top of the combustion chamber provided 80 with outlet ports to the diffusing body of the supplementary top to supply it with water vapors, and means to releasably clamp a tube or a tire to the top of the combustion chamber.

4. A vulcanizer comprising a hollow body having a top section and a bottom section adapted to conjointly form a combustion chamber, said bottom section being adapted to contain a fixed quantity of heating 90 means, a container for water depending into the combustion chamber from the under side of the top section provided with top outlets for the generated vapors of water, a container for the material for a patch, 95 means adapted to restrictively diffuse and vent the vapors of water along the margin of the top, and means to clamp a tube or a tire over the patch container.

5. A vulcanizer comprising a body provided with a combustion chamber and a container for a fixed quantity of heating means, a top over the combustion chamber having a central container for the material for a patch and having its body composed 105 of a nonconducting material but adapted to diffuse and permit the discharge of vapors of water supplied thereto, a container for water extending into the combustion chamber having ports to feed the diffusing material of the top, and means adapted to press a tube or a tire upon the top and a plate to distribute applied pressure over the body of the tire.

6. A vulcanizer comprising a heatable 115 body provided with heating means and a cavity for the material for a patch, bail-like clamp bars arranged one to each side of the body of the vulcanizer and pivoted thereto, one or more cross-bars pivotally 120 and movably attached to one bail and detachably coupled to the other bail to permit of folding the bails upon the body of the vulcanizer, and pressure means removable from the cross connecting bars of the 125 bails.

7. A knock-down vulcanizer comprising a member embodying heat-zone-defining

means, opposing arms pivotally mounted on the member and foldable toward each other, and an adjustable clamping means coacting with the arms to force the material to be vulcanized into position adjacent the heat-zone-defining means.

8. A knock-down vulcanizer comprising a member embodying heat-zone-defining means, a pair of arms carried by the member, one of which arms is foldable over the member, an arm-connecting link releasable from one of the arms to fold toward the member and into position adjacent the foldable arms, and adjustable clamping means 10 coacting with the connecting link to force

the material to be vulcanized into position adjacent the heat-zone-defining means.

9. A vulcanizer embodying an anchor member, a pair of links connected to the member, a third link connecting said pair 20 of links, said three links rockable as to the anchor member, and an adjustable clamping means mounted upon the intermediate link to oppose at different angles the anchor member.
